222,834

COMBINED AIR CONDITIONER FRONT AND SIDE PANELS THEREFOR

Roger F. Chapin, Jr., Columbus, Ohio, assignor to
Westinghouse Electric Corporation

Filed June 10, 1970, Ser. No. 23,420

Term of patent 14 years

Int. Cl. D23—04

U.S. Cl. D23—141

FIG. 1 is a perspective view of an air conditioner front embodying my design; and

FIG. 2 is a side elevational view thereof, the opposite side having the same appearance.

I claim:

The ornamental design for a combined air conditioner front and side panels therefor, substantially as shown and described.
